UNITED STATES PATENT OFFICE

96,486

DESIGN FOR A RADIATOR

Raymond Loewy, New York, N. Y., assignor to
Sears, Roebuck and Co., Chicago, Ill., a corpo-
ration of New York

Application January 4, 1935, Serial No. 54,725

Term of patent 7 years

To all whom it may concern:

Be it known that I, Raymond Loewy, a citizen of France, residing at New York city, in the county of New York and State of New York, have invented a new, original, and ornamental Design for a Radiator, of which the following is a specification, reference being had to the accompanying drawing, forming part thereof.

The figure is a perspective view of a radiator showing my new design and composed of separately cast sections coating to present the appearance of a cabinet, the design being especially

characterized by the provision in the upper part of the front wall of the structure of horizontally elongated parallel air discharge openings formed by the front edges of parallel fins terminating horizontally in forwardly offset relation to the front edges of laterally spaced vertical columns, substantially as shown.

I claim:

The ornamental design for a radiator substantially as shown and described.

RAYMOND LOEWY.
